UNITED STATES PATENT OFFICE.

AUSTIN HERR, OF ST. ELMO, VIRGINIA, ASSIGNOR TO THE EUREKA INSTANTANEOUS OPENING CORSET STEEL COMPANY, OF DOVER, DELAWARE.

CORSET-CLASP.

SPECIFICATION forming part of Letters Patent No. 634,576, dated October 10, 1899.

Application filed February 21, 1899. Serial No. 706,399. (No model.)

To all whom it may concern:

Be it known that I, AUSTIN HERR, a citizen of the United States, residing at St. Elmo, Alexandria county, State of Virginia, have invented certain new and useful Improvements 5 in Corset-Clasps, of which the following is a specification.

My invention relates to corset-clasps; and it consists in constructing the busks, as fully 10 set forth hereinafter, so as to permit the two busks to be locked together at all points by a single movement of the locking device, so as to secure the two parts firmly in position during the time that they are locked or connected 15 and so as to permit the unlocking of all of the studs simultaneously. To this end I construct the parts as fully set forth hereinafter and as illustrated in the accompanying drawings, in which—

20 Figure 1 is a face view of my improved corset-clasp. Fig. 2 is the same of one of the busks. Fig. 3 is a face view of the blades of the latter busk. Fig. 4 is a face view of another blade of the latter busk. Fig. 5 is a 25 transverse section on the line 5 5, Fig. 1.

There are two busks A B in my improved corset-clasp, the busk B, like many others, being provided with headed studs or pins 8, arranged at suitable intervals and adapted 30 to coöperate with the engaging parts on the busk A. This busk A consists of two plates or blades 12, the blade 1 being provided with 35 projections 3 and the blade 2 with similarly-arranged projections 4, the blade 2 either lying upon or beneath and sliding longitudinally in respect to the blade 1, being confined thereto by pins 6 passing from the blade 1 through slots w in the blade 2 and extending through washers 7 and riveted, as 40 shown, or any other suitable fastening means may be employed to permit the blade 2 to slide upon or beneath the blade 1 to a limited extent. Preferably, as shown, the parts are so connected that the projections 4 of the 45 blade 2 in being carried from the projections 3 of the blade 1 will be moved upward, so that naturally the descent of the blade 2 would tend to bring the projections 4 to their lower positions.

50 Each projection 3 has a slot x extending

from the outer end inward and enlarged to form an eye x', adapted to receive the head of the pin 8, the slot x being of sufficient width to permit the passage of the stem of the pin or stud, and each projection 4 is provided with a 55 hook 5, which when the projection 4 is in a lower position will cross a slot x and close the outer end of the same, so that the stem of the stud, after being drawn outward, can pass into the inner portion of the slot x, but 60 on contact with the edge y of the hook 5 is prevented from moving farther outward. When the blade 2 is raised to the position shown in Fig. 2, all of the hooks 5 are carried away from the slots, and the stems of the stud 65 can then be passed inward through the slots x or the heads may be passed upward through the eyes x', and then by longitudinal movement of the blade 2 all the hooks are caused to cross the slots x. Thus the two busks are 70 securely fastened together and cannot be separated until the blade 2 is moved upward. For this purpose it is only necessary for the wearer to bear against the lower end of the blade 2, which may be turned slightly out- 75 ward to afford a bearing, and push it upward, when at once the two busks are unhooked. Whether the blade 2 is pushed downward or not, it will naturally tend to fall or work 80 downward to a locking position, and therefore there will be little danger of displacement in actual use.

It will be seen that the draft of the studs is outward against the hooks 5, and in order to enable them to better withstand the strain 85 the projections 3 extend on both sides of the same, affording lateral bearings in both directions. In order to prevent the outward strain from tending to lift the blade 2 and, in fact, to secure a reverse action, I incline the 90 edges y of one or more hooks inward toward the blade at the outer end, whereby the outward draft tends rather to draw the hooks 5 downward than to lift them and to open the slots.

95 It is not always necessary to have the slots enlarged to form eyes x', as they may be carried back without enlargement, as shown in the bottom position, Fig. 3, in which case the stems of the studs may be passed inward 100

through the slots *x* and will be locked in place by the downward movement of the blade 2, as before described.

The projections 3 4 may be formed in plates of brass or other material riveted to the blades 1 2; but I prefer to form them in one piece with the latter, as it makes the article less bulky. A stud 10 on the block 2 projects through a slot *v* near the top of the blade 1 and constitutes a means of sliding the blade 2 by applying the power at the upper end of the busk. The wearer can thus unlock the upper studs while holding the lower one in position and then return the blade 2 to place, so that the busks remain connected at the bottom only.

Without limiting myself to the precise construction and arrangement of parts shown, I claim as my invention—

1. The combination in a corset-clasp, of a busk consisting of a blade provided with projections at one side, each with a slot extending inward from the outer end, and a second blade sliding longitudinally on the first and provided with hooks rigid therewith arranged to cross said slots to close the outer ends of the same, substantially as set forth. 45

2. The combination in a corset-clasp, of a busk consisting of a blade provided with projections at one side, each with a slot extending inward from the outer end and enlarged to form an eye, and a second blade sliding longitudinally on the first and provided with hooks rigid therewith arranged to cross said slots to close the outer ends of the same, substantially as set forth. 50

3. The combination in a corset-clasp, of a busk consisting of a blade provided with projections at one side, each with a slot extending inward from the outer end, and a second blade sliding longitudinally on the first and provided with hooks rigid therewith arranged to cross said slots to close the outer ends of the same, one or more of said hooks having inclined edges, substantially as set forth. 55

4. The combination in a corset-clasp, of a busk consisting of a blade provided with projections at one side, each with a slot extending inward from the outer end, and a second blade sliding longitudinally on the first and provided with hooks rigid therewith arranged to cross said slots to close the outer ends of the same, the latter blade arranged to slide to carry the hooks away from the slotted projections in an upward direction, substantially as set forth. 60

5. The combination in a corset-clasp, of a busk consisting of plates each consisting of a steel blade with projections at one edge in one piece with the blade, the projections of one blade having slots extending inward from the outer ends, and the projections of the other blade in the form of hooks to close the outer ends of said slots, substantially as set forth. 65

In testimony whereof I have signed my name to this specification in the presence of two subscribing witnesses.

AUSTIN HERR.
